UNITED STATES PATENT OFFICE.

FREDERICK L. HUMESTON, OF NEW HAVEN, CONNECTICUT, ASSIGNOR TO WINCHester REPEATING ARMS COMPANY, OF NEW HAVEN, CONNECTICUT, A CORPORATION OF CONNECTICUT.

HANDLAMP SWITCH.

Application filed February 9, 1923. Serial No. 617,940.

To all whom it may concern:

Be it known that I, FREDERICK L. HUMESTON, a citizen of the United States, residing at 25 Brewster Street, New Haven, in the county of New Haven, State of Connecticut, have invented certain new and useful Improvements in Handlamp Switches; and I do hereby declare the following to be a full, clear, and exact description of the invention, 10 such as will enable others skilled in the art to which it appertains to make and use the same.

This invention relates to battery hand lamps and it provides an improved electric conductor connecting the lamp switch with a terminal of the lamp circuit. The invention includes, as an important part thereof, an insulating sheath for this conductor, the sheath being of an improved construction 20 and possessing features which render its use in conjunction with the conductor very valuable, especially where the hand lamp is provided with a metal casing.

It is well known that a battery hand lamp 25 having a metal casing must be provided with an insulated conductor extending from the switch to one terminal of the lamp circuit, the insulation being required for the purpose of preventing the metal casing from short 30 circuiting the lamp switch. This invention, therefore, includes a metal strip extending from the battery switch to the reflector of the lamp or some other convenient terminal near the lamp bulb, and the circuit is closed 35 in the usual manner by manually connecting the movable element of the switch to this metal strip.

The conducting strip is preferably of special construction, and particularly adapted 40 to be enclosed by an insulating sheath of improved construction. The insulating sheath, which may be of any suitable insulating material, covers two sides and one end of the conducting strip and the sheath preferably comprises a single strip of material, bent back on itself near the central portion 45 of the strip so that it forms an envelope into which the conducting strip may be inserted. The conductor is constructed in such a manner that it serves to prevent lateral 50 displacement of the insulating sheath and it also prevents the free ends of the sheath from moving away from the conducting strip. The improved sheath presents a

smooth rounded edge to the battery when it is being inserted into the hand lamp casing and the conductor is fixed to the casing in such a manner that it is electrically insulated from the casing at all points. 55

The features of this invention mentioned above, as well as various others, may be better understood by referring to the following detailed description, which is to be considered in conjunction with the accompanying drawing, in which— 60

Fig. 1 is a longitudinal section of a battery hand lamp provided with one embodiment of this invention.

Fig. 2 is a longitudinal section of the improved conductor and insulating sheath enclosing the conductor, showing the manner in which it is fixed to the lamp casing. 70

Fig. 3 is a plan view of the parts shown in Fig. 2, portions being cut away to show the construction of the parts beneath. 75

Fig. 4 is a plan view of the improved insulating sheath, a portion being cut away to show the lower part of the sheath.

Fig. 5 is a longitudinal section of the sheath shown in Fig. 4. 80

Fig. 6 is a plan view of the improved conductor, and

Fig. 7 is a longitudinal section of the conductor shown in Fig. 6. 85

Fig. 1 of the drawing shows a battery hand lamp having the usual casing 1, base cap 2, switch 3 and lens 4. The lens is held in place in the usual manner by means of a suitable threaded retaining ring 5, adapted to engage the bell-shaped head 6, which in turn is secured to the casing 1 by screw threads shown at 7. The lamp is also provided with the ordinary reflector 8 and bulb 9, and the casing is adapted to receive a battery 10, yieldingly held in position by 95 the spring 11 in the base cap 2.

In the form of hand lamp chosen for the purpose of illustration, the lamp reflector 8 forms a part of the electric circuit, and, therefore, it is insulated from the retaining ring 5 and head 6 by a suitable grooved ring 12 of insulating material, the grooved ring being interposed between the lens 4 and the metal parts close to the edge thereof. The casing 1 of the lamp is of metal and forms a part of the electric circuit. The switch 3, which may be of any ordinary construction, is permanently fixed to the 100

casing 1 and is provided with the usual push button 13, which may be actuated at will to close the electric circuit.

In the type of lamp shown in the drawing, 5 the reflector 8 may be considered one terminal of the electric circuit and the switch 3 the other terminal. In order that the electric circuit may be closed, an improved conductor 14 is provided, the conductor extending 10 between the switch 3 and the reflector 8. It is obvious that this conductor 14 must be insulated from the casing 1, otherwise the lamp circuit would be permanently closed through the casing 1. Accordingly, an improved insulating sheath 15 is provided for 15 this purpose.

The conductor 14, which is illustrated in the drawing, particularly in Figs. 6 and 7, comprises a single strip of any suitable 20 metal, preferably in sheet form. One end of the conductor is made narrower than the main portion thereof, and this end is turned up at substantially right angles to the main portion of the strip to form a contact point 25 16 adapted to be engaged by the movable element of the switch 3. The other end 17 of the strip 14 is preferably bent into a curved shape which serves as a spring contact adapted yieldingly to engage the reflector 8 of the lamp. A plurality of holes 30 18 are punched in the body portion of the conductor 14 for the purpose of receiving the rivets which serve to fix the conductor to the casing 1 of the lamp. These holes 18 are substantially larger than the rivets, as 35 best shown in Fig. 2. Near the curved end of the conductor 14, a hook 19 is formed by cutting a tongue from the conductor and pressing this tongue downward substantially 40 as shown in Figs. 6 and 7.

The improved insulating sheath 15, one embodiment of which is shown in the drawing, particularly in Figs. 4 and 5, comprises a single strip of flexible insulating material 45 bent back on itself as shown at 20. This sheath may be made of any suitable insulating composition, ordinary pasteboard, or heavy paper being quite satisfactory. This sheath is provided with a slot 21, through 50 which the contact projection 16 of the conductor 14 may extend. The upper part of sheath is also provided with holes 22 corresponding with the holes 18 in the conductor. The holes 22 are substantially smaller 55 in diameter than the holes 18, however, for a purpose hereinafter described. The insulating sheath 15 is preferably wider than the conductor 14 so that it overhangs the edges of the conductor, as best shown in 60 Fig. 3, thus effectively insulating the edges of the conductor from the lamp casing 1. The end of the lower portion of the sheath 15 is provided with a stepped notch indicated at 23. The distance between the portions 24, which form part of the notch 23, is

substantially equal to the width of the conductor 14 and permits the curved section 17 to pass between the portions 24 when the conductor and sheath are assembled.

The improved conductor and sheath may 70 be assembled by spreading apart the upper and lower portions of the sheath 15 and inserting the conductor 14 between these portions until the projection 16 extends through the slot 21 in the sheath. The two 75 parts of the sheath may then be closed together and the inner edge 25 of the notch 23 may be slipped between the hook 19 and the body portion of the conductor 14. This effectively prevents the lower portion 80 of the sheath from moving away from the conductor 14. Ordinary insulating materials are subject to warping by virtue of the moisture absorbed thereby, and the hook 19 prevents the sheath 15 from moving away 85 from the conductor 14 under any conditions. When the conductor and sheath are assembled the portion 17 projects downward 90 between the projections 24 of the lower part of the sheath 15. The curved portion 17 95 and the hook 19 each, therefore, serves to prevent lateral displacement of the lower part of the sheath 15.

The conductor and the sheath may be 95 assembled on the casing 1 by riveting the parts thereto, as best shown in Fig. 2. When the rivets are driven home, the conductor 14 is insulated therefrom by the depressed sections 27 of the lower part of the sheath 15. The rivets 26 draw the lower portion of the sheath 15 into the holes 18 of the conductor and against the upper portion of the sheath, and it will be noted that the lower head of each rivet is substantially 100 flush with the lower face of the insulating sheath 15. In order to make certain that the insulating material enters the holes 18, formed in the conducting strip 14, the edge of each of the holes 22 in the insulating sheath may be cupped or pressed in before 105 the sheath is applied to the conducting strip. The operation of riveting the parts together of course has a tendency to draw in the edge of each of these holes, so that in any event the ultimate shape of the insulating sheath at 110 the points where it is fixed to the conducting strip is substantially as shown in Figure 2. Thus it is apparent that, even if the rivets 26 work loose, the conductor 14 is prevented 115 from coming into direct contact with the rivets 26, by the insulating material 27 interposed between these parts.

By again referring to Fig. 1 it should be 120 clear that this invention provides an improved insulated conductor interposed between the switch 3 and the reflector 8, the conductor being rigidly fixed to the casing 1 in such a manner that it is effectively insulated therefrom and free to warp or buckle without in any way impairing the 125 130

insulation of the conductor or tearing the insulating sheath itself. Means is provided for preventing entirely any displacement of the ends of the insulating sheath. Furthermore, the end of the sheath nearest the base cap 2 presents a smooth rounded edge to the battery 10 when the latter is inserted into the casing 1; thus the battery or the insulating cover 28 thereon has no tendency 10 to tear the insulating sheath 15 or to be torn by it.

It is to be understood that the size, proportions and arrangement of the various parts of this invention may be changed 15 without departing from the spirit of the invention which is not confined to the particular embodiments shown and described, but includes all modifications thereof that fall within the scope of the appended 20 claims. For instance, the conductor 14 in the particular embodiment shown in the drawing, connects the switch 3 with the reflector 8, but it is of course apparent that this conductor may extend between the hand 25 lamp switch and any suitable terminal of the electric circuit of the lamp.

I claim:

1. In a battery hand lamp, a sheet metal casing, a metal conducting strip extending 20 between the hand lamp switch and a terminal of the electric circuit of the hand lamp, rivets for fixing said strip to said casing, and a single strip of insulating material interposed between said conducting 25 strip and the casing and between said conducting strip and the rivets.

2. In a battery hand lamp having a metal casing, an electric conductor extending between the hand lamp switch and a terminal 40 of the electric circuit of the hand lamp, a one piece insulating sheath enclosing said conductor, and means in contact with the casing for rigidly securing said conductor and sheath to the casing and means carried by said conductor for holding one end 45 of the sheath near the conductor while permitting this end to be moved parallel to the conductor.

3. In a battery hand lamp, an electric 50 conductor extending between the hand lamp switch and a terminal of the electric circuit of the hand lamp, an insulating sheath

enclosing said conductor and comprising a single strip of insulating material bent back on itself to form a sheath having a closed 55 end, and means carried by said conductor for preventing lateral displacement of one end of said sheath.

4. In a battery hand lamp, an electric conductor extending between the hand lamp 60 switch and a terminal of the electric circuit of the hand lamp, and an insulating sheath enclosing said conductor and having a notch therein, said conductor having an integral hook 65 engaging the notch in said sheath for preventing one end of the sheath from moving away from the conductor, while permitting movement of this end of the sheath parallel to the conductor.

5. In a battery hand lamp, an electric 70 conductor extending between the hand lamp switch and a terminal of the electric circuit of the hand lamp, an insulating sheath for said conductor, means for fixing the sheath to the central portion of the conductor and means carried by said conductor for holding one end of the sheath near the conductor while permitting this end to be moved parallel to the conductor.

6. In a battery hand lamp, an insulating 85 sheath for a conductor extending from the hand lamp switch to a terminal of the electric circuit of the hand lamp, said sheath comprising a single strip of insulating material bent back on itself to form an envelope 90 for the conductor and to present a smooth rounded edge to the hand lamp battery when it is inserted into the hand lamp casing.

7. In a battery hand lamp, an insulating 95 sheath for a conductor extending from the hand lamp switch to a terminal of the electric circuit of the hand lamp, said sheath comprising a single strip of insulating material bent back on itself to form an envelope 100 for the conductor, said sheath being provided with a slot for receiving an upturned end of the conductor and with a notched end adapted to be held by the conductor from lateral displacement with respect to the conductor.

In testimony whereof I affix my signature.

FREDERICK L. HUMESTON.
